UNITED STATES PATENT OFFICE

OSCAR RICE, OF CHICAGO, ILLINOIS

CONCRETE ANCHOR

Application filed June 25, 1929. Serial No. 373,576.

This invention relates to an improved device for use in connection with building and construction work, such as is broadly referred to in the trade as a concrete anchor.

5 In accordance with the present invention, I provide a novel combination of details, principally defined by two permanent parts, namely the part to be anchored in the concrete and the part to support the complementary brick work or masonry facing structure.

In carrying the invention into effect, I have evolved and produced a novel and economical arrangement of parts characterized by a masonry supported angle or shelf which is adjustable with respect to the complementary part imbedded in the concrete wall.

The particular structural features and advantages and their relative arrangement and association will become more readily apparent from the following description and drawings.

In the drawings:

Figure 1 is a face view of the part of the structure which is anchored in the wall.

Figure 2 is a horizontal section on the line 2—2 of Figure 1.

Figure 3 is a perspective view of the adjusting block.

Figure 4 is a central vertical section through the parts assembled showing the relationship of the angle iron to the anchoring box.

Figure 5 is a horizontal section on the line 5—5 of Figure 4.

Figure 6 is a view showing the device associated with the construction work.

The relatively stationary part of the device is in the nature of a metallic box which is vertically elongated and of general rectangular configuration, the same being represented by the reference character 7. It is formed in its front with a vertical slot 8 communicating with a vertical guideway 9 for the slideable adjusting block 10. The block and box are substantially wedge-shaped in cross section as seen in Figure 2. The block carries a screw threaded stud 11 adapted to accommodate a retaining nut 12. This stud is intended to pass through an

opening in the relatively adjustable parts of the structure which is in the form of an angle iron generally designated at 13. The horizontal flange of this constitutes the so-called shelf.

The upper portion of the box contains a hanger plate or partition member 14, which provides a bearing for the smooth portion of the stem of the bolt 15. The head of the bolt 16 rests on this plate and is arranged in a pocket 17 which accommodates a tool or wrench for turning the bolt. The threaded portion of the stem is propped into and through the screw threaded hole 18 of the adjustable block shown in detail in Figure 3.

It will be observed that the box is formed on opposite sides with outstanding lugs 19 having holes to accommodate the nut equipped and screw threaded portions of the anchoring bail 20. This bail is disposed diagonally with respect to the lug as seen in Figure 6. The reference characters 21 designate webs for reinforcing purposes. These are provided with V-shaped nail receiving notches 22.

The box-like anchor 7 is nailed to the wooden structure of the concrete form before the concrete is poured. The V-shaped notches 22 accommodate the nails (not shown). Then after the concrete is poured the bail 20 becomes anchored therein as seen in Figure 6. Also the box is anchored in the concrete. The adjusting bolt 15 is now put in position and threaded through the openings in the adjusting blocks 10. The angle iron 13 is then put in position over the stud 11, in order to provide a supporting shelf for the masonry facing structure 23, as seen in Figure 6. With this arrangement, the principal feature is the vertical adjustment of the shelf which permits the proper placement of the masonry structure. The adjustment may be made by placing the wrench into the pocket 17 and engaging the head 16 of the bolt 15. In this respect the anchoring box constitutes a reinforcing and backing member for the vertical flange of the angle iron.

It is thought that persons skilled in the art to which the invention relates will be able to obtain a clear understanding of the con-

struction, method of application, and features and advantages after considering the description in connection with the drawings. Therefore, a more lengthy description is believed to be unnecessary.

5. Minor changes in the shape, size and rearrangement of details coming within the field of invention claimed may be resorted to, in actual practice, if desired.

I claim:

10. 1. In a structure of the class described, a hollow open front box-like anchor, a bolt mounted for rotation therein, a block adjustably mounted on said bolt, an angle iron support, and means connecting said support with said block through said open front.

20. 2. In a structure of the class described, in combination, a vertically elongated hollow box-like anchoring body including a bearing plate defining a guide way and a pocket, a bolt suspended from said bearing plate and having its head located in said pocket and its screw threaded stem portion located in said guide way, a block slidable in said guide way and having a screw threaded hole through which the stem portion of said bolt is threaded, said block having an outwardly projecting supporting stud, said body being formed in its front with an opening through which said stud is projected, and an angle iron support, the vertical flange thereof being provided with an opening through which said stud is passed, and a retaining nut carried by said stud and cooperable with said flange.

30. 3. As a new product of manufacture, a concrete anchor comprising a substantially rectangular hollow box like body provided with an internal guide way, an internal horizontal partition defining a top pocket, a bolt suspended from said partition plate and having its head located in said pocket and its stem portion located in said guide way, a block adjustable in said guideway and including a supporting stud and having a screw threaded hole through which the screw threaded portion of said bolt passes.

40. 4. As a new product of manufacture, a concrete anchor comprising a substantially rectangular hollow box-like body provided with an internal guide way, an internal horizontal partition defining a top pocket, a bolt suspended from said partition plate and having its head located in said pocket and its stem portion located in said guide way, a block adjustable in said guideway and including a supporting stud and having a screw threaded hole through which the screw threaded portion of said bolt passes, said body being formed on opposite sides with outstanding lugs and reinforcing webs, said webs being notched to accommodate fastening nails.

5. As a new product of manufacture, a concrete anchor comprising a substantially

rectangular hollow box-like body provided with an internal guide way, an internal horizontal partition defining a top pocket, a bolt suspended from said partition plate and having its head located in said pocket and its stem portion located in said guideway, a block adjustable in said guideway and including a supporting stud and having a screw threaded hole through which the screw threaded portion of said bolt passes, said body being formed on opposite sides with outstanding lugs and reinforcing webs, said webs being notched to accommodate fastening nails, and a bail having its arm portions detachably connected with said lugs.

In testimony whereof I affix my signature.

OSCAR RICE.
